(57) **CLAIM**

The ornamental design for an inflatable half-cylindrical play structure, as shown and described.

DESCRIPTION

FIG. 1 is a perspective view of an inflatable half-cylindrical play structure;

FIG. 2 is a right side view of the of the inflatable half-cylindrical play structure, the left side view (omitted) being a mirror image thereof;

FIG. 3 is a front view of the inflatable half-cylindrical play structure, the rear view (omitted) being a minor image thereof;

FIG. 4 is a bottom view of the inflatable half-cylindrical play structure;

FIG. 5 is a top view of the inflatable half-cylindrical play structure; and,

FIG. 6 is a perspective view of the inflatable half-cylindrical play structure employed in an inflatable play structure system.

The broken line showing of is included for the purpose of illustrating and forms no part of the claimed design.
